CLAIM

The ornamental design for a wireless headset, as shown and described.

DESCRIPTION

FIG. 1 is a perspective view of the wireless headset from the right side;

FIG. 2 is a front elevational view thereof;

FIG. 3 is a rear elevational view thereof;

FIG. 4 is a left side view thereof;

FIG. 5 is a right side view thereof;

FIG. 6 is a top view thereof; and,

FIG. 7 is a bottom view thereof.

The broken lines shown in FIG. 3 and FIG. 4 illustrate portions of the wireless headset that form no part of the claimed design.
